INVENTOR

Hans Guenthermann

UNITED STATES PATENT OFFICE.

HANS GUENTHERMANN, OF MOUNT VERNON, NEW YORK, ASSIGNOR, BY DIRECT AND MESNE ASSIGNMENTS, TO BUTLER BROS., OF NEW YORK, N. Y., A CORPORATION OF ILLINOIS.

DESIGN FOR A PLATE OR SIMILAR ARTICLE.

Application filed October 18, 1922. Serial No. 4,013. Term of patent 7 years.

To all whom it may concern:

Be it known that I, HANS GUENTHERMANN, a citizen of the United States and resident of Mount Vernon, in the county of Westchester and State of New York, have invented a new, original, and ornamental Design for a Plate or Similar Article, of which the following is a specification, reference being had to the accompanying drawing, forming part thereof, which drawing is a plan view of a plate or similar article illustrating my new design.

I claim:

The ornamental design for a plate or similar article, as shown.
